RADIO PAGING MOBILE UNIT

Francis P. Mesarow, Chicago, Ill.

Application November 30, 1954, Serial No. 33,338

Term of patent 14 years

(Cl. D72—1)

Fig. 1 is a front elevational view of a radio paging mobile unit embodying my new design;

Fig. 2 is a rear elevational view of the radio paging mobile unit of Fig. 1;

Fig. 3 is an end elevational view of the radio paging mobile unit of Fig. 1; and

Fig. 4 is a plan view of the radio paging mobile unit of Fig. 1.

I claim:

The ornamental design for a radio paging mobile unit, substantially as shown.
